Primary Examiner—Stella Reid

(57) **CLAIM**

The ornamental design for a pacifier handle, as shown and described.

DESCRIPTION

FIG. 1 is a perspective view of a pacifier handle showing our new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken line showing of the nipple and shield in FIGS. 1-7 is for illustrative purposes only and forms no part of the claimed design.
